(57) CLAIM

I claim the ornamental design for a cosmetic tweezer, as shown and described.

DESCRIPTION

FIG. 1 is a perspective view of a cosmetic tweezer showing my new design;

FIG. 2 is a left side view thereof, the right side view being a mirror image thereof;

FIG. 3 is a top view thereof, the bottom view being a mirror image thereof;

FIG. 4 is a front view thereof; and,

FIG. 5 is a rear view thereof.

The broken lines are shown for illustrative purposes only and form no part of the claimed design.
